[57] CLAIM

The ornamental design for a training football, as shown.

DESCRIPTION

FIG. 1 is a perspective view of a training football showing my new design;

FIG. 2 is a perspective view thereof;

FIG. 3 is a plan view thereof;

FIG. 4 is a bottom view thereof;

FIG. 5 is a left side view thereof;

FIG. 6 is a right side view thereof;

FIG. 7 is a rear elevational view thereof; and,

FIG. 8 is a front elevational view thereof.

The speckled portions in the design reflect a different color or texture compared to the remaining surface portions.
